GAME BOARD OVERLAY

James E. Jones, 305 Vista Trucha,
Newport Beach, Calif. 92660

Filed May 14, 1975, Ser. No. 577,200

Term of patent 14 years

Int. Cl. D21—01

U.S. Cl. D34—5 SS

FIG. 1

FIG. 1 is a top plan view of a game board overlay showing my new design;

FIG. 2 is a front elevational view of said overlay design, the rear elevational view being substantially identical thereto; and

FIG. 3 is a right side elevational view thereof, the left elevational view being substantially identical thereto.

I claim:

The ornamental design for a game board overlay, as shown and described.
